STEAM IRON

Roy H. Edwards, Mansfield, Ohio, assignor to
Westinghouse Electric & Manufacturing Com-
pany, East Pittsburgh, Pa., a corporation of
Pennsylvania

Application May 22, 1942, Serial No. 444,115

10 Claims. (Cl. 38—77)

This invention relates to steam irons and particularly to that class of steam irons which are thermostatically controlled and include a valve-controlled water supply for feeding water at a predetermined rate to a steam generator provided in the iron, and it has for an object to provide an improved steam iron of the character set forth.

It is another object of this invention to provide an improved construction of steam iron in which the rate of water flow to the steam generator and the soleplate temperature are selected by a single manually adjusted means.

In the copending application of Kenneth L. Woodman, Serial No. 382,305, filed March 8, 1941, and assigned to the assignee of the present invention, there is disclosed a steam iron in which the rate of water flow is selected or predetermined automatically by the setting of the thermostat adjusting shaft. It is an object of the present invention to improve the steam iron disclosed in that application and to simplify its assembly.

These and other objects are effected by this invention as will be apparent from the following description and claims taken in connection with the accompanying drawings, forming a part of this application, in which:

Fig. 1 is a side elevational view partly in longitudinal section of an electrically heated steam iron in which the present invention has been incorporated;

Fig. 2 is a top plan view of the iron illustrated in Fig. 1 with the handle removed;

Fig. 3 is an enlarged side elevational view of a cam, looking in the direction of the arrow A in Fig. 1, adapted to actuate the water valve of the iron illustrated in Fig. 1;

Fig. 4 is an enlarged side elevational view of a cam, looking in the direction of the arrow B in Fig. 1, adapted to adjust the soleplate thermostat to maintain the soleplate at a selected temperature;

Figs. 5 and 6 are views similar to Figs. 1 and 2, respectively, and illustrating a modified form of the invention; and

Fig. 7 is a plan view of the adjusting knob of the iron shown in Figs. 5 and 6.

Referring first to the embodiment of the invention illustrated in Figs. 1 to 4, inclusive, there is shown a steam iron, generally indicated 10, which comprises a soleplate 11, a cover member 12, and a handle 13, which are secured together in any suitable manner. The interior of the cover 12 is provided with suitable partitions, such as indicated at 14, which together with the side and top walls of the cover define a liquid-storage

chamber or reservoir 15. This chamber may be filled with water or other vaporizable liquid suitable for dampening clothes through a suitable opening provided in the top of the cover, which opening is normally closed by a removable plug 16 (Fig. 2). The storage chamber may be vented in any desired manner.

The soleplate 11 may be of conventional outline and is preferably provided with an armored electrical heating element 17 embedded therein, as disclosed in the mentioned Woodman application. This heating element may be of well-known construction and comprise an outer metallic tube or sheath 18 having a coiled resistance element 19 supported in spaced, concentric relation thereto by means of highly-compacted heat-conducting, electrical-insulating material.

The heating element 17 is connected to a suitable source of electrical energy by means of conductors 21 (Fig. 1), as well understood in the art. The heating element is connected to these conductors in series with a manually-adjusted thermostat 22 which is supported in a recess provided in the soleplate so as to be responsive to the temperature thereof.

The thermostat 22 is adjusted, to maintain the soleplate at a selected temperature, by means of a knob 23, fixed to a shaft 24, journaled in bearings 25, fixed to the top of the cover 12. The knob 23 is arranged so that the upper portion thereof projects through a window 26 provided in the cover. This knob is provided with a scale 27 adapted to be read in conjunction with an index 28 fixed to the iron adjacent the window 26 for indicating the selected ironing temperature.

The rear end of the rod 24 is provided with a cam 29 which may be fixed thereto or formed integrally therewith, which cam engages the upper end of a rod 30 operatively connected to the thermostat 22. The rod 30 is slidable in a vertical sleeve 31 which extends through the storage chamber 15 and is brazed or otherwise secured in fluidtight manner to the upper and lower walls thereof.

As the shaft 24 is rotated by means of the knob 23, the cam 29 raises or lowers the rod 30 to adjust the thermostat to maintain the soleplate at any desired temperature. The rod 30 is spring-biased upwardly to maintain the same in engagement with the cam 29 and is provided with an adjusting screw 32, the head of which engages the cam 29 to aid in calibrating the thermostat. The thermostat and its adjusting mechanism is preferably arranged so that the high point 33

(Fig. 4) of the cam maintains the thermostat continuously open regardless of the temperature of the soleplate, to provide an "off" position for the iron.

As disclosed in the mentioned application of Kenneth L. Woodman, the heating element 17 is preferably U-shaped. The soleplate is provided with a recess 34 located within the bight of the U-shaped heating element and opening on the ironing surface 35 of the soleplate. The lower end of this recess is closed by means of a removable metallic member or plug 36 which is spaced from the wall 37 of the soleplate overlying the recess to define a steam-generating space within the soleplate. This plug is provided with a raised annular rib or baffle 38 which divides the space within the soleplate into two communicating compartments 39 and 40. Water from the storage chamber 15 is supplied to the circular compartment 39 within the annular baffle, as will appear hereinafter, where it is instantly flashed into steam. The steam thus formed flows over the annular rib into the annular compartment 40 from which it is discharged, through ports 41 provided in the plug, to the material to be pressed.

The storage chamber 15 and the steam-generator are connected together by a bushing member 42 having a passage 43 therethrough. This bushing is received in aligned openings provided in the lower wall 14 of the storage chamber and the upper wall 31 of the soleplate. This bushing is preferably brazed or otherwise secured in fluid-tight relation to the wall 14 and is clamped in fluidtight relation to the soleplate by means of a nut 44 threaded on the lower reduced end of the bushing.

The passage 43 in the bushing connects the interior of the storage chamber with the interior of the steam-generator. The upper end of this passage flares outwardly to provide a valve seat 45 which is engageable by the lower tapered end 46 of a valve stem 47 to close the passage. The valve stem extends through and is guided for vertical movement by a sleeve 48 secured in fluid-tight relation, as by brazing, to the upper wall of the storage chamber and telescoped over the reduced upper end of the bushing 42. This sleeve is provided with suitable apertures 49 which permit water in the storage chamber 15 to enter the passage 43 when the valve is open.

The upper end of the valve stem extends through a bracket 51 fixed to the iron. This bracket also serves as a stop or abutment for a compression spring 52 coiled about the upper end of the valve stem. The lower end of this compression spring engages a shoulder 53 formed on the valve stem so that the spring tends to bias the valve stem into valve-closing position to stop the flow of water from the storage chamber 15 into the steam generator.

The valve is opened and closed by means of a bell-crank lever 54 secured to the valve stem, below the shoulder 53. The lever may be either fixed or rotatable on the valve stem. One arm 55 of the bell-crank lever projects beyond the side of the handle 13 through a suitable slot or recess provided therein and is adapted to be manually moved between the full line position shown in Fig. 2 and the dotted line position there shown, and is maintained in either of these positions by means of a toggle or over-center spring 56, fixed at one end to the bracket 51 and at its other end to the arm 55. Suitable stops 57 prevent the movement of the arm 55 beyond the two positions.

The short arm 58 of the bell-crank lever is adapted to engage or be moved clear of a cam 59 carried on the forward end of the rotatable rod 24, depending on the position of the arm 55.

5 In the full line position of the lever 54 (Fig. 2) the arm 58 thereof is clear of the cam 59 and the spring 52 maintains the water valve closed. This position of the lever is identified by the legend "Dry" on the iron. By swinging the lever to the dotted line position (Fig. 2) the arm 58 of the lever overlies the cam 59 and, depending upon the position of the cam, may be raised thereby to open the water valve. This position of the lever may be termed the steam position and is so identified by the legend "Steam."

10 The cam 59 is of such contour as to open the water valve any desired amount between closed position and a maximum open position, depending upon the temperature adjustment of the thermostat, to provide a rate of water flow to the steam generator which will supply the correct amount of steam for the type of material to be pressed. Thus the cams 29 and 59 are correlated so that for each temperature setting of the thermostat, affected by the cam 29, the cam 59 will open the water valve a certain amount to provide the correct rate of water flow to the steam generator. It is to be understood that the cam 59 may be shaped to provide any change in the rate of flow from a minimum to a maximum value as the knob 23 is turned to adjust the soleplate temperature. Further, the iron may be used either as a dry iron or as a steam iron without changing the setting of the knob 23 by manipulating the arm 55 of the bell-crank lever 54 to either the "Dry" position or the "Steam" position.

15 In Figs. 3 and 4, the cams 59 and 29 have been shown on an enlarged scale in the position they assume when the knob 23 is set at "off." In each of these figures, the parts of the cams which engage the respective abutments 58 and 32 when the knob is adjusted to maintain the soleplate at a given temperature level have been identified 20 by the same legends appearing on the knob itself. Thus, when the knob 23 is turned to bring the legend "linen" opposite the index 28, the point on the cam 29 identified by the legend "linen" in Fig. 4 will overlie the screw head 32 25 and adjust the thermostat 22 to maintain the soleplate at a temperature suitable for ironing linen. Similarly, this setting of the knob 23 will bring the point of the cam 59 identified by the legend "linen" beneath the arm 58 to raise the 30 valve stem sufficiently to provide a rate of water flow to the steam generator sufficient to correctly dampen linen.

35 In Figs. 3 and 4, reference circles 59a and 29a, respectively, have been provided to better show the amount the valve stem is raised by the cam 59 as the knob 23 is turned from "rayon" to "linen," and the amount the thermostat adjusting rod 30 is permitted to rise as the knob 23 is turned from the "off" position to the "linen" position. In these figures, curved arrows have also been applied to indicate the direction of rotation of the cams as the knob is turned throughout the range of adjustment from "off" to "linen."

40 In Figs. 5 and 6, there is shown a slightly different embodiment of the invention in which the bell-crank lever 54 of the iron 10 may be omitted while permitting the iron to be used either as a dry iron or a steam iron, and in which the rate of water flow is automatically determined by the 45 temperature setting of a single control knob.

The modified iron, generally indicated 60, as in the case of the iron 10, includes a soleplate 61, a cover member 62, and a handle 63 which are secured together in any suitable manner. The soleplate 61 and its heating element 64, the steam generator 65, and thermostat 66 for controlling the temperature of the soleplate may be identical with that shown in Fig. 1 and described in detail above, and therefore, a description of these parts need not be repeated. The interior of the cover 62 is also provided with partitions, such as 67, to define a water storage chamber 68. As in the case of the iron 10, water from the storage chamber 68 is supplied to the steam generator 65 under the control of a valve, which includes a stem 69 and a valve seat 71 provided in the passage 72 extending from the storage chamber to the interior of the steam generator.

The valve stem 69 projects through a bushing 73 secured in fluidtight relation to the top wall of the cover, as by brazing. The upper end of the valve stem extends to the top of the handle 63 and carries a knob 74. The valve stem is normally biased upwardly into "open" position by means of a spring 75 compressed between the top wall of the cover 62 and a stop or abutment 76 fixed to the valve stem.

The thermostat operating rod 77 is also biased upwardly by means of a spring 78 compressed between the top of the guide sleeve 79 and a stop or abutment 81 fixed to the operating rod. The guide sleeve is brazed or otherwise secured in fluidtight relation to the upper and lower walls of the storage chamber 68.

The positions of the valve stem 69 and the thermostat operating rod 77 are determined, respectively, by means of a pair of cams 82 and 83. These cams, which are disc shaped, are carried by and rotatable with a vertical shaft 84 journaled at its lower end in a guide bearing 85, fixed to the top of the cover 62. The upper reduced end of this vertical shaft is supported in a guide bracket 86, fixed to the handle. The shaft is provided with a manually adjusted knob 87, a portion of which projects through a window 88 provided in the handle.

This knob 87 carries a double or divided scale 89 as shown in Fig. 7. It will be noted that one scale is identified as a "steam" scale and the other as a "dry" scale. These scales are adapted to be read in conjunction with an index 91 provided on the handle adjacent the window 88 to indicate the temperature for which the thermostat has been adjusted. The scales may be graduated in any desirable manner, as, for example, in types of material to be pressed or steamed when the soleplate is at the temperature selected.

The lower, disc-like cam 83 which engages the stop 81 carried by the thermostat operating rod 77, is shaped to have a low point 92 and a high point 93 which are diametrically opposite each other. When the knob 87 is turned to bring the low point 92 over the stop 81, the thermostat operating rod 77 is depressed sufficiently to maintain the switch of the thermostat 66 continuously open and thereby provide an "off" position for the iron. The high point 93 of the cam 83 represents the maximum height to which the thermostat operating rod 77 can be raised by the spring 78 and fixes the maximum temperature setting of the thermostat.

Between the high point 93 and the low point 92 of the cam 83, the surface of the cam is designed to gradually depress the stop 81 to provide an infinite number of positions of adjustment of the

thermostat between its maximum high temperature setting and its "off" position. Each half of the cam between the high and the low points is shaped the same so that the thermostat is adjustable between maximum high and "off" through one-half a turn of the adjusting knob 87.

The upper cam 82, which engages the stop 76 to adjust the water valve, is shaped so that through approximately one of these one-half turns of the adjusting knob 87 the cam maintains the valve closed. In Fig. 5 the iron is shown adjusted to maintain the soleplate at a temperature substantially midway between the maximum high and the "off" position while holding the valve closed. With the iron in this condition, the "dry" scale will be visible through the window 88 and the operator can readily ascertain that the iron is conditioned to be used only as a dry iron.

20 The second half of the cam 82 is shaped to provide a high point 94. When knob 87 is turned to bring the high point 94 of cam 82 over the stop 76, the valve is open to its maximum value. The cams 82 and 83 are arranged on the shaft 84 so that the high points 94 and 93 engage the stops 76 and 81 simultaneously. The second half of the cam 82 gradually decreases from the high point 94 to the low level of the other half of the cam, so that for approximately the remaining one-half turn of the knob 87 the water valve is adjusted to gradually decrease the rate of flow of water to the steam generator from a maximum value. This second half of the cam 82 engages the stop 76 of the valve at the time the "steam" scale of the knob 87 is visible through the window 88.

In using the iron 60, the operator sets the knob 87 to select the correct ironing temperature for the particular material to be ironed. If the operator desires to use the iron only as a dry iron, she will use the "dry" scale of the knob, the water valve under this condition being maintained continuously closed by the low half of the cam 82.

45 If the operator desires to steam the clothes while ironing them, the operator uses the "steam" scale of the knob 87 to select the correct ironing temperature. In selecting the correct ironing temperature by means of the knob 87, it will be understood that the cam 83 is positioned so that it adjusts the thermostat to maintain the soleplate at that temperature. When using the "steam" scale, the cam 82 is simultaneously positioned to allow the water valve to open to provide the proper rate of water flow to the steam generator.

Since it may be desirable to shut off the flow of water to the steam generator while the iron is adjusted to be used as a steam iron, and since it is also necessary to stop the flow of water to the steam generator while the iron is coming up to heat, as from room temperature, means have been provided to permit the water valve to be closed even though the cam 82 is positioned to permit the spring 75 to raise the valve stem 69 clear of the valve seat 71. This means may be of any desired form but is here shown as comprising a spring-pressed detent 95. This detent includes a small sphere mounted in the handle 63 and which is spring pressed against the side wall of a reduced portion 96 of the valve knob 74. A peripheral groove 97 provided in the reduced portion 96 is adapted to seat the detent 95 when the water valve is in its closed position

and prevent the spring 75 from raising the valve stem to "open" position. When it is desired to open the valve, the knob 74 may be grasped and moved upwardly to release the detent 95 from the groove 97, the open position of the valve stem then being determined by the position of cam 82.

While the invention has been shown in several forms, it will be obvious to those skilled in the art that it is not so limited, but is susceptible of various other changes and modifications without departing from the spirit thereof, and it is desired, therefore, that only such limitations shall be placed thereupon as are specifically set forth in the appended claims.

What is claimed is:

1. A steam iron comprising a soleplate, means for heating said soleplate, adjustable thermostatic means for controlling the temperature of said soleplate, a steam generator carried by said soleplate, means including a valve for supplying water to said steam generator, said valve being adjustable to vary the rate of flow of water to said steam generator, a shaft journaled on said iron independently of said thermostatic means and said valve, manually-operable means for rotating said shaft, a plurality of cam means carried by said shaft, said cam means being adapted to simultaneously adjust said thermostatic means and said valve on rotation of said shaft.

2. A steam iron comprising a soleplate, means for heating said soleplate, adjustable thermostatic means for controlling the temperature of said soleplate, a steam generator carried by said soleplate, means including a valve for supplying water to said steam generator, said valve being adjustable to vary the rate of flow of water to said steam generator, a member journaled on said iron, manually-operable means for rotating said member, a plurality of cam means carried by said member and adapted to simultaneously adjust said thermostatic means and said valve, and a manually shiftable lever movable between a first position and a second position and effective to operatively connect one of said cam means to said water valve in one of said positions to adjust the same and in the other position to disconnect said cam means from said water valve.

3. A steam iron comprising a soleplate, means for heating said soleplate, adjustable thermostatic means for controlling the temperature of said soleplate, a liquid-storage chamber carried by said soleplate, a steam generator carried by said soleplate, means including a valve for conveying water from said storage chamber to said steam generator, said valve being adjustable to vary the rate of flow of water therethrough, a valve-operating member, movable abutment means carried by said valve-operating member, a horizontally extending rotatable shaft journaled on said iron in spaced relation above said thermostatic means, cam means carried by said shaft and adapted to adjust said thermostatic means, second cam means carried by said shaft and adapted to adjust said valve, said abutment means being selectively movable into and out of engagement with said last-mentioned cam means to selectively render said second cam means effective or ineffective to adjust said valve.

4. A steam iron comprising a soleplate, means for heating said soleplate, adjustable thermostatic means for controlling the temperature of said soleplate, a steam generator carried by said soleplate, means including a valve for supplying water to said steam generator, said valve being adjustable to vary the rate of flow of water to

said steam generator, a member journaled on said iron, manually-operable means for rotating said member, first and second cam means fixed to said member, said first cam means being operatively associated with said thermostatic means and adapted to adjust the same through a range of adjustment during a half revolution of said member and through substantially the same range of adjustment during the remaining half revolution, the second cam means being operatively associated with said valve for adjusting the same, said second cam means being arranged to maintain the valve closed during a half revolution of said member and to adjust said valve

10 between closed position and a maximum open position during the remaining half revolution of said member, said first and second cam means being fixed to said member in such a manner that said first cam means adjusts said thermostatic means through said range of adjustment during a half revolution of said member while said second cam means maintains said valve closed.

5. A steam iron comprising a soleplate, means 25 for heating said soleplate, adjustable thermostatic means for controlling the temperature of said soleplate, said thermostatic means including a longitudinally movable rod for adjusting the same, a steam generator carried by said soleplate, means including a valve for supplying water to said steam generator, said valve including a longitudinally movable valve stem and being adjustable to vary the rate of flow of water to said steam generator, a movable member mounted 30 on said iron, manually operable means for moving said member, and cam means carried by said member for simultaneously moving said rod and said stem longitudinally to adjust said thermostatic means and said valve on movement of said 35 member by said manually operable means.

6. A steam iron comprising a soleplate, means for heating said soleplate, adjustable thermostatic means for controlling the temperature of said soleplate and including a vertically-extending adjusting rod, a steam generator carried by said soleplate, means including a valve for supplying water to said steam generator, said valve having a vertically-extending valve stem spaced from said adjusting rod and being adjustable to 45 vary the rate of flow of water to said steam generator, a movable member mounted on said iron between said adjusting rod and said valve stem, means for moving said member, a pair of cam means carried by said member and associated respectively with the adjusting rod of said thermostatic means and the valve stem of said valve, said cam means being adapted to actuate said rod and said stem to simultaneously adjust said thermostatic means and said valve on movement of said member, and manually operable means for closing said valve irrespective of the adjustment of its cam means.

7. A steam iron comprising a soleplate, means for heating said soleplate, a steam generator 65 carried by said soleplate, means including a valve for supplying water to said steam generator, means including a cam for adjusting said valve, said cam being shaped to maintain said valve closed for approximately the first half of the range of movement of said cam and to adjust said valve from its closed position to a maximum open position through the second half of its range of movement, thermostatic means for controlling the temperature of said soleplate, and 70 75 cam means movable with said first-mentioned

cam means to adjust said thermostatic means, said second cam means being shaped to adjust said thermostatic means through a range of adjustment during the first half of the range of movement of said first cam means and through substantially the same range of adjustment during the second half of the range of movement of said first cam means.

8. A steam iron comprising a soleplate, means for heating said soleplate, a steam generator carried by said soleplate, means including an adjustable valve for supplying water to said steam generator, first means for adjusting said valve, said first means being movable and arranged to maintain said valve closed for an initial portion of the range of movement of said first means and to adjust the size of the opening through said valve over a second portion of its range of movement, adjustable means for controlling the temperature of said soleplate, and second means movable with said first means to adjust said temperature controlling means, said second means being arranged to adjust said temperature controlling means through a range of adjustment during the initial portion of the range of movement of said first means and through substantially the same range of adjustment during the second portion of the range of movement of said first means.

9. A steam iron comprising a soleplate, a cover overlying said soleplate and secured thereto, a handle mounted over said cover, means for heating said soleplate, adjustable means for controlling the temperature of said soleplate, a steam generator carried by said soleplate, means including a valve for supplying water to said steam generator, said valve being adjustable to vary the rate of flow of water to said steam generator,

a horizontal shaft movably mounted on said iron within said cover, means carried by said shaft for adjusting said valve, means carried by said shaft for adjusting said temperature controlling means, the means carried by said shaft being adapted to simultaneously adjust said temperature controlling means and said valve on movement of said shaft, and manually-operable means for moving said shaft to effect the simultaneous adjustment of said temperature controlling means and said valve, said cover having an opening therein through which said manually operable means is exposed for manual manipulation, said opening and manually operable means being located substantially beneath the central portion of said handle.

10. A steam iron comprising a soleplate, means for heating said soleplate, a steam generator carried by said soleplate, means including an adjustable valve for supplying water to said steam generator, first means for adjusting said valve, said first means being movable and arranged to maintain said valve closed for one portion of the range of movement of said first means and to adjust the size of the opening through said valve over another portion of its range of movement, adjustable means for controlling the temperature of said soleplate, and second means movable with said first means to adjust said temperature-controlling means, said second means being arranged to adjust said temperature-controlling means through a range of adjustment during said one portion of the range of movement of said first means and through at least a part of the same range of adjustment during said other portion of the range of movement of said first means.

ROY H. EDWARDS.
